UNITED STATES PATENT OFFICE

2,596,764

TEXTILE MACHINE

José Dotti, Santa Fe, Argentina, assignor to
Euterio Lorenzo Dotti, Santa Fe, Argentina

Application May 9, 1946, Serial No. 668,386

5 Claims. (Cl. 19-127)

1

The present invention refers to improvements in textile machines of the kind comprising a succession of combs or quills provided with means for freezing and moving fibre, such as textile frame machines, drawing or sliver frames, carding machines, combing machines, etc.

The main object of this invention is to provide machines, of the kind specified, with a series of rods or similar units conveniently arranged so as to enter between two or more rows of quills or combs, the function of said rods being to remove and to move the fibre contained in said combs or quills.

A further object of the present invention is to operate the machines such as, for example, drafting or sliver frames, at speeds the maxima of which correspond to the speed that can be reached by the drafting or feeding devices which are associated with the drafting or sliver frames, thereby obtaining a considerable increase in output, more than ten-fold the output of the conventional machines.

In order that the invention may be more clearly understood and readily carried into effect, preferred embodiments of same, explicative but in no way to be considered as limitations, have been illustrated in attached drawings, wherein:

Figure 1 is a diagrammatic side view of a drawing or sliver frame of a textile machine, placed between the feeding and drawing cylinders and provided with the improvements of this invention, and

Figure 2 is a modification of the device illustrated in Figure 1.

As is known, textile machines for drawing and parallelizing textile fibers comprise a machine provided with inlet or feeding cylinders and drawing or delivery cylinders, the cylinders being spaced apart a distance, termed the pitch or reach, which is related to the length of the fibers. Support means are provided for the fibers between the feeding cylinders and the drawing cylinders.

According to the present invention, the support means consists of transverse rows of combs or quills and a plurality of rods interpositioned between the rows of combs for removing fibers from the combs. Fibers are fed from the feeding cylinders onto the support means between the combs or quills and are carried by the combs up to the drawing cylinders. Inasmuch as the drawing cylinders turn at a speed which is greater than the motion of the combs, the fibers are removed from the combs rapidly and slide along the combs thus bringing about the combing, par-

2

alleling and drawing step. At this time, the direction of movement of the combs is changed so that the combs slide along and over the rods so that the rods remove the fibers from the combs.

As is shown in Fig. 1, the textile machine comprises a drawing or sliver frame, consisting of a pair of endless parallel chains or belts 1, which support the ends of transversely disposed combs or quills 2. The belts are positioned intermediate the feed cylinders or rolls, to the right of the belts in Fig. 1, and the drawing cylinders or rolls, to the left of the belts in Fig. 1. The chains or belts 1 move over guides or guide-sections 3, and are actuated by chain wheels or cylinders 4, the shaft of one of which is connected to a motor unit, not shown in the drawings.

Entering between successive combs or quills 2, are transverse rods 5, which are mounted on another pair of endless chains or belts 6, moving over proper guides 7 and driven by means of chain wheels or cylinders 8, the belts 6 and guides 7 are mounted to the outside, or exteriorly, of the belts 1 and guides 3, so that the belts 1 and associated quills 2 may pass between the belts 6 and guides 7.

As shown in Fig. 1, another group of transverse rods 9 may be arranged above this assembly, said rods being supported with their ends by a pair of endless chains or belts 10 passing over corresponding chain wheels or cylinders 11.

The rods 9 enter between the combs or quills 2 on the upper stretch of the endless chain or belt 1, and exert pressure on the fibrous material fed into the machine, so that the quills or combs 2 are forced into the material.

When the moving parts of the described assembly are in motion, in the direction indicated by arrows in Figure 1, it will be noted that, at the rear end of the machine the pair of endless chains or belts 6 do not descend at the same time with the endless chains or belts 1, but that the former move horizontally along a greater stretch before moving downwardly.

The object of this is to allow the combs or rows of quills 2, to bear during their downward movement along this differential stretch of their journey, against the rods 5, and to slide on same, as a consequence of which said rods remove and transport the fibrous material situated in said combs or quills 2.

Fig. 2 illustrates a modification of the above described machine of the invention.

In Fig. 2, two pairs of endless chains and combs and rods of construction similar to that shown in Fig. 1, have been superposed, analogous parts

of the two units being identified with the same reference numbers.

The pairs of endless chains or belts 21 supporting combs or quills 22 are trained over rotatable chain wheels or cylinders 24 and stationary guides 23, the two units being positioned between the feed cylinders, to the right, and the drawing cylinders, to the left. The pairs of endless chains or belts 26 carrying transverse rods 25 are trained over chain wheels or cylinders 28 and stationary guides 27, the arrangement being such that the rods 25 enter into the row of horizontally moving combs 22 of the associated comb assembly. The guides 27 extend a short distance beyond the run off end of the endless chains or belts 21 to properly guide the rods 25 downwardly and out of engagement with the combs 22.

A comparison of the two units will show that they are identical, the upper unit being inverted and the comb assemblies of the two units combining in the drawing or slivering action. Each unit of the total assembly is very similar to the unit disclosed in Fig. 1. The two pairs of endless chains or belts 21 in the assembly shown in Fig. 2 are so arranged that the upper and lower horizontal portions which are parallel to each other and move in the same direction are so closely adjacent each other that the combs 22 on the lower belts 21 enter into the spaces formed between the comb 22 on the upper belts 21.

The improvement disclosed by this invention can be adapted by a great number of textile machines; therefore, that which has been illustrated and described should only be taken as an example, which is capable of being modified in construction and detail without departing from the scope of the invention and the appended claims.

I claim:

1. In a drawing frame for a textile machine, a pair of spaced parallel endless flexible carriers, a series of combs mounted in spaced relation on said carriers, said combs extending transversely of said pair of endless carriers and being supported with both their ends by said carriers, at least two spaced rotatable members over which said endless carriers are trained so as to form a horizontal portion having a feed end and a running off end, at least one of said rotatable members being connected to a driving means, and a second pair of spaced parallel endless flexible carriers mounted to the outside of said first named pair of endless carriers, a series of rods mounted in spaced relation on said second pair of carriers and each extending transversely thereof and supported with both their ends by said second pair of carriers, means for moving said second pair of carriers in their longitudinal direction, said second pair of endless carriers being longer than the first named pair of endless carriers and being arranged to surround the entire first named endless carriers, a horizontal portion of the second pair of carriers having its rods positioned in the spaces between the combs on the horizontal portion of the first mentioned carriers, the combs when changing their direction of movement at the running off end of said endless carriers slidably engaging said rods and thereby removing any fibrous material which may adhere to the combs.

2. In a drawing frame for a textile machine, a pair of spaced parallel endless flexible carriers, a series of combs mounted in spaced relation on said carriers, said combs extending transversely of said pair of endless carriers and

being supported with both their ends by said carriers, at least two spaced rotatable members over which said endless carriers are trained so as to form a horizontal portion having a feed end and a running off end, at least one of said rotatable members being connected to a driving means, a second pair of spaced parallel endless flexible carriers mounted to the outside of said first named pair of endless carriers, a series of rods mounted in spaced relation on said second pair of carriers and each extending transversely thereof and supported with both their ends by said second pair of carriers, means for moving said second pair of carriers in their longitudinal direction, said second pair of endless carriers being longer than the first named pair of endless carriers and being arranged to surround the entire first named endless carriers, a horizontal portion of the second pair of carriers having its rods positioned in the spaces between the combs on the horizontal portion of the first mentioned carriers, the combs when changing their direction of movement at the running off end of said endless carriers slidably engaging said rods and thereby removing any fibrous material which may adhere to the combs, and a third pair of spaced parallel endless flexible carriers supporting another series of transverse rods at both their ends, means for moving said third pair of endless carriers in their longitudinal direction, said third pair of endless carriers being substantially shorter than said first mentioned endless carriers and being arranged outside said second pair of carriers in such a manner that the rods of said third pair of endless carriers enter the spaces between the combs of the horizontal portion of the first mentioned carriers to press the fibrous material fed to the frame into said spaces.

3. In a drawing frame for a textile machine, a pair of spaced parallel endless flexible carriers, a series of combs extending transversely between said flexible carriers and supported with both their ends by said carriers, fixed horizontal guide means over which a portion of said endless carriers is moved, means for moving said endless carriers in their longitudinal direction, a second pair of spaced parallel endless flexible carriers of greater length than and positioned exteriorly of said first mentioned pair of endless carriers, a series of transverse rods mounted in spaced relation between said second pair of endless carriers and supported by the same, means for driving said second pair of endless carriers, said second pair of endless carriers being arranged to surround said first mentioned pair of endless carriers in such a manner that the rods enter the space between the combs on the first mentioned pair of carriers when the latter move over said fixed horizontal guide means and that the combs when moving off one end of said guide means slidably engage said rods to thereby remove any fibrous material adhering to the combs.

4. In a drawing frame for a textile machine, a pair of spaced parallel endless flexible carriers, a series of combs extending transversely between said flexible carriers and supported with both their ends by said carriers, fixed horizontal guide means over which a portion of said endless carriers is moved, means for moving said endless carriers in their longitudinal direction, a second pair of spaced parallel endless flexible carriers of greater length than and positioned exteriorly of said first mentioned pair of endless carriers, a series of transverse rods mounted in spaced relation between said second pair of endless carriers

riers and supported by the same, means for driving said second pair of endless carriers, said second pair of endless carriers being arranged to surround said first mentioned pair of endless carriers in such a manner that the rods enter the space between the combs on the first mentioned pair of carriers when the latter move over said fixed horizontal guide means and that the combs when moving off one end of said guide means slidably engage said rods to thereby remove any fibrous material adhering to the combs, and a third pair of spaced parallel endless flexible carriers supporting another series of transverse rods at both their ends, means for moving said third pair of endless carriers in their longitudinal direction, said third pair of endless carriers being substantially shorter than said first mentioned endless carriers and being arranged outside said second pair of carriers in such a manner that the rods of said third pair of endless carriers enter the spaces between the combs of the horizontally guided portion of the first mentioned carriers to press the fibrous material fed to the frame into said spaces.

5. In a drawing frame for a textile machine, a pair of spaced parallel endless flexible carriers, a series of combs extending transversely between said flexible carriers and supported with both their ends by said carriers, fixed horizontal guide means over which a portion of said endless carriers is moved, means for moving said endless carriers in their longitudinal direction, a second pair of spaced parallel endless flexible carriers of greater length than and positioned exteriorly of said first mentioned pair of endless carriers, a series of transverse rods mounted in spaced relation between said second pair of endless carriers and supported by the same, means for driving said second pair of endless carriers, said second pair of endless carriers being arranged to surround said first mentioned pair of endless carriers in such a manner that the rods enter the space between the combs on the first mentioned pair of carriers when the latter move over said fixed horizontal guide means and that the combs when moving off one end of said guide means slidably engage said rods to thereby re-

move any fibrous material adhering to the combs, a third pair of spaced parallel endless flexible carriers of the same length as said first mentioned pair of spaced parallel endless flexible carriers and supporting another series of combs extending transversely between said third pair of flexible carriers, another fixed horizontal guide means over which a portion of said third pair of endless carriers is moved, said third pair of flexible carriers being arranged so that the combs carried by a portion of the same project into the spaces between the combs on that portion of the first mentioned endless flexible carriers which is supported by said first mentioned horizontal guide means, and a fourth pair of spaced parallel endless flexible carriers supporting another series of transverse rods at both their ends, means for moving said third and fourth pair of endless carriers in their longitudinal direction, said fourth pair of endless carriers being positioned exteriorly of and arranged to surround said third mentioned pair of endless carriers in such a manner that the rods enter into the space between the combs on said third mentioned pair of carriers when the latter move over said second mentioned fixed horizontal guide means and that the combs when moving off one end of said last mentioned guide means slidably engage said rods to thereby remove any fibrous material adhering to the combs carried by said third pair of endless carriers.
